UNITED STATES PATENT OFFICE.

LEONARD F. FULLER, OF SAN FRANCISCO, CALIFORNIA, ASSIGNOR TO FEDERAL TELEGRAPH COMPANY, OF SAN FRANCISCO, CALIFORNIA, A CORPORATION OF CALIFORNIA.

RADIOTELEGRAPHY.

1,309,283.

Specification of Letters Patent.

Patented July 8, 1919.

Application filed September 4, 1917. Serial No. 189,524.

To all whom it may concern:

Be it known that I, LEONARD F. FULLER, a citizen of the United States, and a resident of the city and county of San Francisco and State of California, have invented 5 certain new and useful Improvements in Radiotelegraphy, of which the following is a specification.

The invention relates to means for signaling and particularly to means of signaling with arc radio transmitters.

An object of the invention is to provide means for signaling involving interrupting and reestablishing the arc.

Another object of the invention is to provide means for interrupting and reestablishing the arc by varying the length of the arc gap.

The invention possesses other advantages, some of which, with the foregoing, will be set forth at length in the following description where I shall outline in full that form of the invention which I have selected for illustration in the drawing accompanying and forming part of the present specification. It is to be understood, however, that the invention as expressed in the claims is not limited to the specific embodiments shown in the drawing.

The drawing is a diagrammatic representation of the signaling system of my invention.

The transmission system comprises an arc oscillation generator, including the electrodes 2-3 between which the arc is formed. One of the electrodes, preferably the negative electrode 3, is grounded and the other electrode 2 is connected to the antenna 4 through the variable inductance coil 5. Direct current is supplied to the arc radio generator by the generator 6 and a choke coil 7 is arranged in the lead 8 which is connected to the electrode 2. The arc is subjected to a strong transverse magnetic field produced by the magnet coils 9 which may be separately excited or arranged in series in the lead 8.

Signaling is accomplished by varying the length of the arc gap to extinguish and ignite the arc and this is preferably accomplished by moving one of the electrodes; in the present construction, electrode 2 being movable. In operation, the length of the arc gap is increased to such distance that

the arc goes out and then the electrodes are brought sufficiently close together to reestablish the arc and are then separated to the position of proper oscillating arc length, at which time the radio energy waves are transmitted. The individual signal is then terminated by increasing the length of the arc gap to extinguish the arc. These various operations are performed automatically and at telegraphic speed, and signaling is accomplished with a transmission key in the usual manner.

Secured to the electrode 2 and insulated therefrom is a solenoid plunger or core 12 which is movable in a direction to increase the length of the arc gap by the spring 13 and is movable in the opposite direction by the effect of the current flowing in the solenoid 14. The solenoid is arranged in series with the battery 15 and the signaling key 16 which, when depressed, closes the circuit 17 and causes the electrode 2 to be moved to shorten the arc gap. In order to reignite the arc, the electrodes must be moved much closer together than their position of proper oscillating arc length and then they must be separated to such position. Stops are provided for halting the movement of the electrode 2 when it reaches the arc ignition position and for halting it when it reaches the position of proper oscillating arc length, and also for stopping it in its position of greatest arc gap length. An adjustable screw 18 arranged to contact with an ear 19 on the plunger limits the backward movement of the plunger and an adjustable screw 20 adapted to contact with a metallic ear 21 arranged on and insulated from the plunger, limits the forward movement of the plunger. Arranged in the solenoid circuit is a spring pressed switch 22 adapted to be opened by the electromagnet 23, arranged in series with the battery 24, the ear 21 and the stop 19, so that when the electrode 2 has moved a sufficient distance to ignite the arc, the contacts 21 and 19 are brought into engagement, closing the circuit through the electromagnet 23 and opening the switch 22. This causes the solenoid 14 to be deenergized and allows the spring 13 to move the plunger 12 to lengthen the arc.

Arranged in the path of the ear 18 is the core 25 of the solenoid 26, which is normally pressed upward by the spring 27.

On the backward movement of the plunger 12, the ear 18 contacts with the core 25 which holds the electrode 2 in proper position to establish the proper oscillating arc length. 5 On the forward movement of the plunger 12 from its rearmost position, the plunger 25 must be depressed to permit the ear 18 to pass and this is accomplished by connecting the solenoid 26 in parallel with the solenoid 14, so that when the key 16 is depressed, the solenoid 26 is energized simultaneously with solenoid 14 and the core 25 is lowered from the path of the ear. When the switch 22 is opened, the spring 27 moves the core 25 10 into position to engage the backwardly moving ear 18.

Means are also provided for removing the core 25 from the path of the ear 18, to permit the arc gap to be lengthened to 20 interrupt the arc. Surrounding the solenoid 26 is a solenoid winding 28, in series with the battery 29 and the key contacts 31 and 32. When the key is released, after having been depressed, the contacts 31 and 32 are 25 brought into engagement closing the circuit through the solenoid winding 28, thereby withdrawing the core 25.

Signaling is therefore accomplished at 30 telegraphic speed by the operation of the key 16, the depression of the key serving to cause a radio frequency wave train to be transmitted, the duration of the train depending upon the length of time that the key is held depressed. The depression of 35 the key causes the electrode 2 to be moved from the position shown, to the ignition position 2^a and thence to the oscillating arc position 2^b. As the electrodes wear, the length of the arc is adjusted by the nut 33 40 engaging a screw 34 secured to the normally stationary electrode 3.

I claim:

1. An arc system for radio signaling comprising two electrodes between which an arc 45 is to be formed, normally spaced apart a distance greater than the arc length, electro-magnetic means for moving one of said electrodes relatively to the other whereby the arc is ignited, and the key for controlling 50 said electro-magnetic means.

2. An arc system for radio signaling comprising two electrodes between which an arc is formed, electro-magnetic means for bringing the electrodes into proximity whereby 55 the arc is formed and means for separating said electrodes to the position of proper oscillating arc length.

3. An arc system for radio signaling comprising two spaced electrodes, a current 60 supply connected to said electrodes, electro-magnetic means for bringing said electrodes together whereby an arc is formed, means for separating said electrodes to the posi-

tion of proper oscillating arc length and 65 means for lengthening the arc gap to extinguish the arc.

4. An arc system for radio telegraphy comprising two spaced electrodes, a current supply connected to said electrodes, a solenoid, a core connected to one electrode and 70 associated with said solenoid, a circuit for said solenoid, the energizing of said circuit serving to bring the electrodes together and means operative by the movement of the electrode for opening the solenoid circuit. 75

5. An arc system for radio telegraphy comprising two spaced electrodes, a current supply connected to said electrodes, a solenoid, a core connected to one electrode and 80 associated with said solenoid, a circuit for said solenoid, the energizing of said circuit tending to move the one electrode toward the other, a spring resisting said movement and means operative by the movement of said one electrode into arc igniting 85 position with the other electrode, to open said circuit, whereby the spring separates said electrodes.

6. An arc system for radio telegraphy comprising two spaced electrodes, a current 90 supply connected to said electrodes, a solenoid, a core connected to one electrode and associated with said solenoid, a circuit for said solenoid, the energizing of said circuit tending to move the one electrode toward the 95 other, a spring resisting said movement, means operative by the movement of said one electrode into arc igniting position with the other electrode to open said circuit, whereby the spring separates the electrodes, 100 and means for stopping the separating movement when the arc gap is of proper oscillating arc length.

7. An arc system for radio telegraphy comprising two spaced electrodes, a current 105 supply connected to said electrodes, a solenoid, a core connected to one electrode and associated with said solenoid, a circuit for said solenoid, the energizing of said circuit tending to move the one electrode toward the other, a spring resisting said movement, means operative by the movement of said one electrode into arc igniting position with the other electrode to open said circuit, whereby the spring separates the electrodes, 110 means for stopping the separating movement when the arc gap is of proper oscillating arc length and means for releasing said stopping means whereby the arc gap is 115 lengthened to extinguish the arc. 120

In testimony whereof, I have hereunto set my hand at San Francisco, California, this 27th day of August, 1917.

LEONARD F. FULLER.
